UNITED STATES PATENT OFFICE

JAMES E. ANNEN, OF MILWAUKEE, WISCONSIN, ASSIGNOR TO THE NATIONAL PAPER CAN COMPANY, OF MILWAUKEE, WISCONSIN, A CORPORATION OF WISCONSIN

CONTAINER

Continuation of application Serial No. 436,102, filed January 10, 1921. This application filed March 9, 1923. Serial No. 624,042.

This application is a continuation of application Serial No. 436,102, filed by myself and George O. Frostad on January 10, 1921.

5 My invention relates to containers, and particularly to containers having an opening at the top which may be closed by a snap closure disk. My invention has to do particularly with containers of the above character which are made of paper or other fibrous material.

10 An object of my invention is the production of a container of the above character and from the material indicated, which is plain and simple in appearance and in which all edges of the material are concealed and the closure is effected completely so that the contents may be safely kept within the container. Another object of my invention is the production of such an article which is thoroughly reinforced at its upper end, and wherein there is provided a seat for the closure disk, the said reinforcement and seat preferably being unitary and constituting a unitary part of the body material from which 25 the container is made.

20 Other advantages of my invention will be apparent upon a reading of the following description taken in connection with the accompanying drawings forming a part hereof, and in which:

25 Figure 1 is a top plan view of the container with the closure disk in place;

Figure 2 is a longitudinal section through the center of the container;

30 Figure 3 is an enlarged detail sectional view showing the arrangement of the upper portion of the container;

Figure 4 is an enlarged detail sectional view showing a modified arrangement of the upper portion of the container;

40 Figure 5 is an enlarged detail sectional view of a further modification of the upper portion of the container;

45 Figures 6, 7 and 8 are enlarged detail views

of further modifications shown in vertical cross section.

Referring to the drawings, the body 1 which is of any suitable material of the character indicated is bent inwardly at 2 and downwardly at 3, and flanged outwardly, forming a groove 4. It is then flanged inwardly producing the flange 5. It is then bent outwardly at 6 and upwardly at 7 and then back upon itself at 8. The vertical portions 7 and 8 fill the space between the body 1 and the downward portion 3. The vertical portion 8 in Figures 3 and 4 terminates just above the groove 4, thus allowing for the outwardly flanged part constituting the groove 4. The portion above described are accurately formed as shown in the drawings by the application thereto of pressure by any suitable die or other forming apparatus, but the pressure thereon is not sufficient to cause any deformation of the material or to cause the same to flow, as has heretofore been considered advisable and necessary in the construction of articles of this general character. A disk closure 9 may be snapped into the position shown in the drawings from the top, and is securely held in position by reason of the flexible nature of the material and the construction claimed. The lower side of the disk rests upon the horizontal portion 5. In the embodiment of the invention shown in Figures 2 and 3 of the drawings, a small space is left between the portions 5 and 6.

In the modification shown in Figures 4 and 5, the space which is shown between the layers 5 and 6 of the flange in Figure 3 is omitted, the two layers in the construction of Figures 4 and 5 being in contact with each other. The parts in Figure 4 corresponding to parts as shown in Figure 3 are marked with the same numeral with the letter *a* affixed.

In the modification shown in Figure 5, the material is continued downwardly at 10, below the groove, whereas in the other modifications the material terminates above the

groove. The parts shown in Figure 5 corresponding to similar parts in Figure 3 are marked with the same numerals with the letter *b* attached. In Figures 4 and 5, certain of the bends or corners are square, whereas in Figure 3 they are round. The corners in each of these modifications may be round or square, as desired.

A further change in the construction as shown in Figure 5 is that the groove is pressed outwardly on all of the layers constituting the upper portion of the container. The various modifications, however, have many essential features in common, and it is evident that many other modifications of the details may be made in the construction without departing from the principles of my invention.

In Figures 6, 7 and 8 are illustrated modifications in which the groove 4 is omitted, the closure disk being held frictionally by the lip of the container. In these figures, the reference numerals corresponding to those in the other figures are employed with, however, the letters *c*, *d* and *e*, respectively. In Figure 6, the material is bent upwardly at 7^c and then terminates. In Figure 7, the material is bent upwardly at 7^d , downwardly at 8^d , the vertical portion 8^d in this case extending down somewhat further than in the construction shown in Figure 2. In Figure 8 the material is bent outwardly at 6^e , but is not extended up between the plies of the lip. In all these constructions the material is bent back from the edge of the seat, so that there is no exposed raw edge.

By reason of the construction shown in the drawings and described herein, a container of the character described is produced which has the advantages of a plurality of thicknesses of material at the top or lip portion, and also at the edge of the disk closure, thus providing for an outward flanging of the material at the groove 4, without deforming or weakening the material at the top, where it is desired that the container should have maximum strength and rigidity.

Furthermore, in my container the paper is doubled back upon itself so that there is no exposed edge of the material at the lip of the container. This construction affords a double thickness folded over instead of a single thickness with an exposed edge.

A further advantage of my construction is that when snapping the disk into place, the end 8 of the material will have a tendency to spring inward after the disk has passed over the portion 3, thus keeping the overhanging lip intact. This overhanging lip will be kept intact or brought back into shape again by the inward pressure of the end 8 of the material, even though the overhanging lip is slightly changed during the placing in position of the disk. This is an advantage over the construction wherein there is a free exposed edge, in which construction there is

nothing to bring the overhanging lip back into proper condition.

A further advantage of my construction is that lighter material may be used with a given rigidity at the lip portion of the container than would be possible in a construction wherein an edge of the material is exposed.

A further advantage of my construction is that with the reinforced seat 5 there is a flexibility which maintains a perfect seat at all times. During the passage of the disk over the overhanging lip 3, this flexibility lends itself admirably to the reformation of the overhanging lip after the disk is snapped into place, this reformation automatically taking place by reason of the flexibility produced by the reinforced seat. Furthermore, the absence of any exposed edge of the material gives a more finished and more perfect appearance to the article than is possible where an exposed edge is present. The anchoring of the edge also aids in maintaining the parts in shape.

By the construction shown and described, the material from which the container is made is of uniform thickness and construction, and the entire container, aside from the closure disks at the ends thereof, is preferably made of a unitary piece of material. This is of great benefit in the manufacture of these articles which, of necessity, must be inexpensive, but nevertheless fulfill certain requirements in the trade that they shall be reasonably rugged and of substantial endurance. This device has a further advantage that both ends of the portion comprising the closure disk seat are rigidly fastened; therefore, the flange 5, 6 upon which the disk rests, while rigid enough to form a complete closure, is nevertheless flexible enough to afford the advantages above set forth. The tightness of the closure is also increased by the formation of the groove 4, which, by reason of the fact that the fibres of the material are not deformed, has a certain amount of inherent flexibility, which it does not lose in the construction shown. The presence of such flexibility at that point adds to the tightness of the joint between the disk and the material at the groove.

The expression "face to face", used in certain of the claims in defining the relationship of the seat and the portion lying in substantial parallelism to it, is not to be taken to imply that the two portions referred to must necessarily be in contact, as there may be a separation of such portions, such, for example, as shown in Figures 2, 3 and 6.

I desire it to be understood that my invention is not limited to the exact details shown and described, as many changes may be made without departing from the spirit of my invention as set forth in the appended claims.

I claim:

1. A paper container having the edge of its body portion folded inwardly and downwardly to form the lip of the container, and then folded inwardly and downwardly and outwardly to form a closure-receiving seat, and then upwardly and inwardly and downwardly within the fold of the lip. ceiving seat projecting inwardly beyond the container wall, the seat being formed of paper and having the end portion thereof bent inwardly from the edge of the seat to lie in substantial parallelism to the seat and transversely of the container to form a finished seat edge, and a lip portion beyond the seat comprising at least three thicknesses of paper, the lip portion having a closure receiving groove adjacent the seat. 70
2. A container having the material at the top thereof bent inwardly and downwardly, then outwardly, then downwardly and inwardly to form a groove, the last mentioned inward fold projecting substantially horizontally and terminating in a downward and outward fold so that the material is folded back upon itself to form a lip of double thickness, and then projecting upwardly and being folded back upon itself to fill the space between the outer and inner layers at the top, thus affording a plurality of thickness at the top, a plurality of thicknesses at the groove and a plurality of thicknesses in the lip whereby the container is strengthened and given rigidity. 75
3. A container having the material at the top thereof bent inwardly and downwardly and then outwardly, downwardly and inwardly to form a groove, the last inward fold projecting substantially horizontally and then being doubled back upon itself to form a double lip, and then projecting upwardly between the outer and inner layers at the top of the container and being bent back upon itself to fill the space between said outer and inner layers at the top. 80
4. A container having an uninterrupted wall terminating in a lip, and a closure receiving seat within the wall adjacent the lip, the closure receiving seat comprising a plurality of plies of paper exclusive of the ply forming the outside of the container and extending transversely of the container in substantial parallelism, the paper being of sufficient strength to form the desired seat and being unreinforced. 85
5. A paper container having a closure receiving seat projecting inwardly beyond the container wall, the seat being formed of paper and having the end portion thereof bent inwardly from the inner edge of the seat to lie in substantial parallelism to the seat, face to face therewith, and transversely of the container to form a finished seat edge, the paper being of sufficient strength to form the desired seat and being unreinforced. 90
6. A paper container having a closure receiving seat projecting inwardly beyond the container wall, the seat being formed of paper and having the end portion thereof bent inwardly from the edge of the seat to lie in substantial parallelism to the seat, face to face therewith, and transversely of the container to form a finished seat edge, and a lip portion beyond the seat comprising at least three thicknesses of paper. 95
7. A paper container having a closure re- 100
